CLAIM

The ornamental design for a hand trolley for handling goods as shown and described.

DESCRIPTION

1. Hand trolley for handling goods

1.1 : Front

1.2 : Back

1.3 : Left

1.4 : Right

1.5 : Top

1.6 : Bottom

1.7 : Perspective

1.8 : Perspective

1.9 : Perspective view in the first unfolded configuration

1.10 : Perspective view in the second unfolded configuration

FIG. **1.1** is a front view of a hand trolley for handling goods showing our new design, shown in a folded configuration; FIG. **1.2** is a rear view thereof, shown in the folded configuration; FIG. **1.3** is a left side view thereof, shown in the folded configuration; FIG. **1.4** is a right side view thereof, shown in the folded configuration; FIG. **1.5** is a top view thereof, shown in the folded configuration; FIG. **1.6** is a bottom view thereof, shown in the folded configuration; FIG. **1.7** is a perspective view thereof, shown in the folded configuration; FIG. **1.8** is another perspective view thereof, shown in the folded configuration; FIG. **1.9** is a perspective view thereof, shown in a first unfolded configuration; FIG. **1.10** is a perspective view thereof, shown in a second unfolded configuration.
